CLAIM

The ornamental design for a weighted hand grip for walking poles, as shown and described.

DESCRIPTION

FIG. 1 is a front right top perspective view of the weighted hand grip according to the present invention;

FIG. 2 is a back left bottom perspective view of the weighted hand grip of FIG. 1;

FIG. 3 is a left side view of the weighted hand grip of FIG. 1;

FIG. 4 is a front view of the weighted hand grip of FIG. 1;

FIG. 5 is a right side view of the weighted hand grip of FIG. 1;

FIG. 6 is a back view of the weighted hand grip of FIG. 1;

FIG. 7 is a top view of the weighted hand grip of FIG. 1;

FIG. 8 is a bottom view of the weighted hand grip of FIG. 1;

FIG. 9 is a front right top perspective view of a walking pole that includes the weighted hand grip of FIG. 1.

Portions or features of the weighted hand grip shown in broken lines in the drawings form no part of the claimed design.
